[57] CLAIM

The ornamental design for a forearm for compact rapid-fire weapons, as shown and described.

DESCRIPTION

FIG. 1 is a side elevational view of forearm for compact rapid-fire weapons showing our new design, the broken line showing of the weapon is for illustrative purposes only and forms no part of the claimed design.

FIG. 2 is a top plan view of the new design for a forearm for compact rapid-fire weapons as set out in FIG. 1. FIG. 3 is a bottom plan view of the new design for a forearm for compact rapid-fire weapons as set out in FIG. 1.

FIG. 4 is a front elevational view of the new design for a forearm for compact rapid-fire weapons as set out in FIG. 1.

FIG. 5 is a rear elevational view of the new design for a forearm for compact rapid-fire weapons as set out in FIG. 1.

FIG. 6 is a side elevational view of the new design for a forearm for compact rapid-fire weapons opposite the side elevation view of FIG. 1.
